UNITED STATES PATENT OFFICE.

JAMES H. RAND, OF NORTH TONAWANDA, NEW YORK.

INDEX.

1,418,466.

Specification of Letters Patent. Patented June 6, 1922.

Application filed October 3, 1919. Serial No. 328,124.

To all whom it may concern:

Be it known that I, JAMES H. RAND, a citizen of the United States, and resident of North Tonawanda, in the county Niagara 5 and State of New York, have invented new and useful Improvements in Indexes, of which the following is a specification.

This invention relates to indexes and consists in certain improvements hereinafter 10 described and particularly pointed out in the claims, upon indexes of the character shown in Letters Patent of the United States, No. 1,025,997 issued to me May 14, 1912.

15 As illustrated in my said former patent and as heretofore used in practice, indexes of this type have had a series of individual or single sheaths or "tubes," removably and interchangeably mounted in the frame, for 20 holding the index slips. Such indexes are extensively used in commercial and mercantile establishments for lists of names. It is sometimes desired to associate with the names additional memoranda or items of information, and such memoranda or items 25 are often of a temporary or changing character while the names are relatively permanent. It is possible to meet requirements of this sort in indexes as heretofore constructed only by using the sheath or tube adjacent to the sheath holding the name slip, for a slip bearing the desired additional memorandum or item, thus alternating the temporary memorandum slips with the more 30 permanent name slips throughout the series; but in removing the sheaths from the frame, or in inserting fresh sheaths into the frame, the two associated sheaths are apt to become 35 displaced or separated, and inconvenience 40 and confusion results owing to the fact that there is often no way of telling to which name sheath a separated information sheath may belong.

The principal object of this invention is 45 to overcome this difficulty by providing a double compartment or "twin tube" holder for the index slips so that the information slip while in use will always remain associated with its appropriate name slip. Other 50 features of the invention will be herein-after described and particularly pointed out in the claims.

In the accompanying drawings which illustrate one embodiment of the invention,— 55 Figure 1 is a front elevation of a part of an index containing the invention, parts being broken away;

Figure 2 is a vertical section, on an enlarged scale, of part of said index;

Figure 3 is an enlarged detail partly in 60 horizontal cross-section and partly in plan;

Figure 4 is a rear view of one of the index slip holders;

Figure 5 is an enlarged section of one 65 of the holders through the entrance opening on line 5—5 of Fig. 1; and

Figure 6 is a face view of a pair of index slips.

The index frame may be of usual construction, and as herein shown consists of a back 70 A, preferably of sheet metal, having its opposite side margins bent to form inwardly extending flanges *a*, *a*, providing channels for the ends of the sheaths or holders.

Each holder comprises a pair of relatively 75 long and narrow, parallel, closed-faced sheaths 1 and 2, made of transparent, resili- 80 ent sheet material such as sheet celluloid. In the form herein illustrated said sheaths are separately formed and fastened together; but they may be integrally formed as shown in another application filed concurrently 85 herewith. The front face of each sheath has an inwardly bent lip 3, thus forming with the back of the sheath a pair of compartments for the index slips. The sheath 1 has a rear flap 4 and the sheath 2 has a 90 rear flap 5, one or both of said flaps being wider than the face of the sheath so that the flaps will overlap when assembled as shown, bringing the front faces side by side. The flaps are cemented or otherwise fastened together.

The two sheaths of each pair are prefer- 95 ably made of sheet celluloid of contrasting colors, the compartment for the name slip being of one color and the compartment for the information slip being of another color, to enable the user more readily to identify the item for which he is looking.

The end of one sheath of each pair, prefer- 100 ably the one intended for the more fre- 105 quently removed index slip, is made with an opening in its front face, spaced a little distance from the end of the holder, through which the index slip may be inserted or removed without removing the holder from the frame. Such entrance opening may be made by cutting away the face of the sheath, as shown at 6, for a sufficient dis- 110 tance from the end of the holder to position the entrance of sheath 2 outside of the frame channel.

The index slips 7 and 8 (Fig. 6) of paper

- or the like are inserted or removed endwise, into or from their respective compartments, the slip 7 containing the name or other relatively permanent matter being placed in 5 sheath 1, from which it cannot be removed without removing the holder from the frame, and the slip 8 containing temporary or changing data being placed in sheath 2, in which it can be inserted or from which it 10 can be removed through the opening 6 without disturbing the holder. The end of slip 8 overlies the flange *a* which holds it in a readily accessible position. Both sheaths might if desired be provided with an entrance opening outside of the frame channel, but it is preferred to protect the more permanent index slip against accidental dislodgement by inserting it through the extreme end of the sheath, whereby it is effectively locked in place by the frame channel. 15 What I claim is:
1. A holder for index slips comprising a pair of parallel, united compartments arranged side by side and adapted to hold 20 separate index slips.
  2. A holder for index slips comprising a pair of parallel, united compartments arranged side by side and adapted to hold 25 separate index slips, the entrance opening of one compartment at least being spaced from the end of the holder.
  3. A holder for index slips comprising a pair of parallel, united compartments arranged side by side and adapted to hold 30 separate index slips, one at least of said compartments having an opening in its front face to admit of the insertion or removal of an index slip therethrough.
  4. A holder for index slips comprising a 35 pair of relatively long and narrow, parallel, closed-face sheaths of transparent resilient material, arranged side by side and united to form a pair of compartments adapted to hold separate index slips.
  - 45 5. A holder for index slips comprising a pair of relatively long and narrow, parallel, closed-faced sheaths of transparent resilient material, arranged side by side and united to form a pair of compartments adapted to hold 50 separate index slips, the sheaths of the pair being of contrasting colors.
  - 55 6. A holder for index slips comprising a pair of relatively long and narrow, parallel, closed-faced sheaths of transparent resilient material, arranged side by side and united to form a pair of compartments adapted to hold 60 separate index slips, the entrance opening of one sheath at least being spaced from the end of the holder.
  - 65 7. A holder for index slips comprising a pair of relatively long and narrow, parallel, closed-faced sheaths of transparent resilient material, arranged side by side and united to form a pair of compartments adapted to hold 70 separate index slips, the end of the

front face of one sheath being cut away to admit of the insertion or removal of an index slip.

8. A holder for index slips comprising a pair of relatively long and narrow, parallel, closed-faced sheaths, separately formed of transparent resilient material fastened together side by side to form a pair of compartments adapted to hold separate index slips. 75

9. A holder for index slips comprising a pair of relatively long and narrow, parallel, closed-faced sheaths, separately formed of transparent resilient material of contrasting colors fastened together side by side to 80 form a pair of compartments adapted to hold separate index slips.

10. A holder for index slips comprising a pair of relatively long and narrow, parallel, closed-faced sheaths, separately formed of transparent resilient material fastened together side by side to form a pair of compartments adapted to hold separate index slips, the entrance opening of one of said sheaths being spaced from the end of the 85 holder. 90

11. A holder for index slips comprising a pair of relatively long and narrow sheaths separately made of transparent, resilient, sheet material folded to form a closed front 95 face and a rear flap, said sheaths being fastened together with their rear flaps overlapping and their front faces side by side.

12. A holder for index slips comprising a pair of relatively long and narrow sheaths 100 separately made of transparent, resilient, sheet material folded to form a closed front face and a rear flap wider than the front face, said rear flaps overlapping and being fastened together, and the front faces being 105 arranged side by side.

13. An index comprising a frame having flanges forming inwardly facing channels, and a holder for index slips mounted in the frame with its ends engaged by said channels, said holder comprising a pair of parallel, united compartments arranged side by side, the entrance opening of one compartment at least being positioned outside of the channel. 110

14. An index comprising a frame having flanges forming inwardly facing channels, and a holder for index slips mounted in the frame with its ends engaged by said channels, said holder comprising a pair of parallel, united compartments arranged side by side, the entrance opening of one compartment at least being positioned outside of the channel and an index slip removably held in said compartment with its end projecting 115 through said entrance opening and overlying the frame flange. 120

Signed by me at North Tonawanda, N. Y., this 30th day of Sept., 1919.

JAMES H. RAND.
